UNITED STATES PATENT OFFICE

165,457

THEATER LOGE CHAIR

Alfred C. Hoven and Walter E. Nordmark, Grand Rapids, Mich., assignors to American Seating
Company, Grand Rapids, Mich., a corporation of New Jersey

Application May 18, 1950, Serial No. 10,022

Term of patent 14 years

(Cl. D15—8)

To all whom it may concern:

Be it known that we, Alfred C. Hoven and Walter E. Nordmark, citizens of the United States, residing at Grand Rapids, in the county of Kent and State of Michigan, have invented a new, original, and ornamental Design for a Theater Loge Chair, of which the following is a specification, reference being had to the accompanying drawings, forming a part thereof.

Figure 1 is a front and left-hand side perspective view of a theater loge chair showing our new design; and

We claim:

The ornamental design for a theater loge chair, as shown.

ALFRED C. HOVEN.

WALTER E. NORDMARK.
